UNITED STATES PATENT OFFICE

HARRY E. NEWTON, OF HARDY, IOWA

GRAPPLE FOR STORAGE BATTERIES AND THE LIKE

Application filed May 28, 1930. Serial No. 456,479.

The invention relates to means for handling storage batteries and other like devices, and has for its principal object the provision of a grapple that is reasonable in cost of manufacture, easy and comfortable to manipulate, and that is extremely effective in operation.

The invention will be described in detail hereinafter and will be found illustrated in the accompanying drawings, in which

Figure 1 is a side view in elevation of the improved grapple showing it applied to a conventional storage battery.

Figure 2 is an end view of Figure 1,

Figure 3 is a top plan view of the grapple,

Figure 4 is a longitudinal sectional view on a plane indicated by the line 4—4 of Figure 3, and

Figures 5 and 6 are detailed sectional views on planes indicated by lines 5—5, and 6—6, respectively, of Figure 4.

In the drawings similar reference characters are used to designate corresponding parts in all of the views.

In Figures 1 and 2, the improved grapple is shown applied to a conventional storage battery A having loop handles B secured to the ends thereof, and the grapple is indicated at 1 and comprises two members 2 and 3, each of which are formed of elongated strips of metal or other suitable rigid material that are hingedly connected together end to end as shown at 4. The strips 2 and 3 are provided with downturned portions 5 and 6, respectively, and have their free ends offset outwardly as shown at 7 and 8, respectively with the extremities of said offset portions 7 and 8 inturned as shown at 9 and 10, respectively. The extremities 9 and 10 and the adjacent portions of the offset portions 7 and 8, respectively, slotted as shown at 11 and 12, respectively, to provide means by which the grapple may be employed to lift batteries and other articles having T-shaped handles, the slots 11 and 12 being provided to receive the stems of such T-shaped handles.

In order to strengthen the portions of the plates 2 and 3 adjacent to the hinged portion 4, and also to provide a comfortable hand-

hold for supporting the grapple, the opposite edges of said strips are curled upwardly as shown at 13 and 14, respectively, said curled edges being tapered outwardly from the hinged portions 4, to more effectively strengthen the grapple adjacent to the hinged portions, and also providing a more comfortable handhold.

What is claimed is:—

1. A grapple for storage batteries and the like, comprising two strips of rigid material hingedly secured together end to end, each of said strips being downturned intermediate of their ends, the extremities of said downturned portions being inturned to provide grappling jaws, and the side edges of the hinged ends of the strips being curled upwardly to strengthen said portions of the strips and to provide a handhold, said upwardly curled edges tapering in width from the hinged portion outwardly therefrom.

2. A grapple for storage batteries and the like, comprising two strips of rigid material hingedly secured together end to end, each of said strips being downturned intermediate of their ends, outwardly offset portions on the free ends of said downturned portions having inturned extremities providing grappling jaws, and the side edges of the hinged ends of the strips being curled upwardly to strengthen said portions of the strips and to provide a handhold, said upwardly curled edges tapering in width from the hinged portion outwardly therefrom.

In testimony whereof I affix my signature.

HARRY E. NEWTON.
